UNITED STATES PATENT OFFICE.

FRANK W. SKINNER, OF TOMPKINSVILLE, NEW YORK.

CONSTRUCTION OF SHEET-PILEING, &c.

No. 866,232.

Specification of Letters Patent.

Patented Sept. 17, 1907.

Application filed February 16, 1907. Serial No. 357,775.

To all whom it may concern:

Be it known that I, FRANK W. SKINNER, a citizen of the United States, residing at #50 Sherman avenue, Tompkinsville, in the county of Richmond and State 5 of New York, have invented a new and useful Improvement for the Construction of Sheet-Piling or other Substructure-Work Below the Surface of the Ground, of which the following is a specification.

My invention relates to appliances for forming a 10 trench or cavity below the surface of the ground for the reception of sheet piles, successive units of other forms of sheeting or portions of other structures.

The principal elements are a series of driving units, generally duplicates, each of which in its simplest 15 form consists essentially of two detachable sides and a removable core. The units being driven successively in a continuous line, displace their volume of earth and form a structure, usually temporary, of any required length, height and thickness, the latter being 20 small in comparison with the other dimensions. After the units are driven the cores can be withdrawn, leaving two parallel walls separated by an interior space of the thickness of the core in which sheet piles or other members can be placed or another structure 25 formed. All the principal parts of the units are separable and removable, but the cores, which may be single pieces or composed of several pieces, may be solid or hollow, and may completely or partially fill the space between the side pieces, are removed first, 30 having served merely to separate and space the outside pieces and strengthen them during driving. The outer or side pieces may be of any suitable material, as wood or steel; they may be flat or curved plates, or rolled or riveted sections; and they may 35 overlap, engage each other, be interlocked, be driven in contact or may be driven with alternate spaces between them.

Heretofore it has been impossible to make an extremely narrow earth trench of great depth, and all 40 trenches have been made by direct excavation, the sheeting when required, being done by separate and independent operations on opposite sides. By this invention the trench is formed without excavation, the earth being displaced without removal, by the 45 driving units, and a great advantage being often derived by the compression of the soil in driving. This single operation also provides sheeting for both sides of the trench and enables the core to be withdrawn without its place being filled by earth pressed in 50 from the outside as would be done if single piece units were driven and withdrawn. Great economy results from the combined formation and sheeting of the trench, simultaneously, at a single operation and from the ability to make the driving units so small 55 and so strong that they can easily be driven in very hard ground and under conditions where it would be

impossible to construct ordinary trenching as well as in quicksand where they can be driven with the greatest ease, in both cases providing for the ultimate assembling of much wider and lighter permanent units of 60 construction than could be placed independently, and securing the final results at a small part of the cost by any other method known to me.

Figure 1 is an end elevation, Fig. 2 is a side elevation at X X, and Fig. 3 is a transverse section at Y Y, 65 of the simplest form of driving unit composed of three pieces a solid full size core, 1 and two side pieces 2 2. Fig. 4 is an end view of two such units driven in sequence. Fig. 5 is a transverse section through the lower end of a unit provided with a driving point or 70 shoe. Fig. 6 is an end elevation of a unit in which the core is composed of two separate pieces and the side pieces are stiffened with flanges and have web projections to engage the adjacent unit. Figs. 7, 8, 9, and 10 are end elevations of successive groups of units 75 driven in sequence and show the serial operations and conditions of driving and redriving the successive units and inserting sheet piles or other construction in the spaces vacated by their cores. Fig. 11 is a top view and Fig. 12 is a transverse section on V V, of the 80 outside members of several units after part of the cores have been withdrawn and they are braced and separated by special appliances. Fig. 13 is a plan and Fig. 14 is a transverse section on T T, of the side pieces of several units driven in sequence and alined after the 85 withdrawal of the cores, by horizontal beams separated by wedges.

In all figures the same parts are indicated by the same reference numbers.

In Figs. 1 2 3 and 4 each driving unit consists of two 90 side pieces 2 2, separated by a solid core detachably connected to them at top and bottom. The side pieces are preferably of a cross section adapted to secure strength and rigidity without causing unnecessary friction or displacement in driving. The lower ends may 95 be square or beveled as shown to draw against the preceding unit as driven. The core, of approximately the same width as the side pieces, may be placed with its edges flush with theirs, or preferably as shown, may be set with one edge projecting beyond the corresponding 100 edges of the side pieces to form a tongue engaging the groove formed by the opposite edges of the corresponding driving unit. The core may project beyond the lower edge of the side pieces to form a pilot or cutting edge, or it may be even with them or they may project beyond it and be bent together so as to draw together as driven and so hold firm and close to the core even without fastenings. The lower ends of the core and side pieces may be secured together during driving by detachable clamps or by a cap, 4, or shoe which 105 remains in the ground when the other members of the driving unit are withdrawn. The upper ends of the

core and side pieces may be secured together during driving by bolts 3, or detachable clamps removed when the core is withdrawn. Bolts, 5 5, keys, or wedges may engage holes through their flanges to maintain the 5 alinement and connect successive side pieces after the core are withdrawn.

In Fig. 5, the detachable shouldered driving point or shoe, 6, is adapted to separate the side pieces 2 2, after the core 1, is withdrawn and is held firmly in position during driving by U-bar clamps, 7, which may engage grooves in the shoe to prevent their displacement.

In Fig. 6, projecting web plates 8 8, are riveted to the side pieces 2 2, to engage the side pieces of the adjacent driving unit and provide permanent connection with it after the cores are withdrawn. The cores are made with a plurality of separate sections, 9 9, which are more easily withdrawn than a single-piece core. The open space inclosed between the core sections and 20 the side pieces is closed at the lower end to exclude earth and other materials, by a cap, filler or shoe which may be similar to 6 in Fig. 5.

Fig. 7 shows two units like that of Fig. 6, driven in sequence and one of its core sections removed and a wedge or separator, 11, driven in its place between the upper ends of the side pieces to maintain them in their proper relative positions and resist the earth pressure.

Fig. 8 is an end view of three similar units driven in sequence with a second core section replaced by a second wedge, 12, and the first wedge 11, withdrawn to permit the entrance of a section of permanent sheet piling, 13, in the space between the side pieces.

Fig. 9 shows the fourth operation and is an end view of four units driven in sequence, a third core section 35 has been removed and a second unit, 14, of sheet piling has been inserted between the side pieces and interlocked with the preceding unit 13. Fig. 10 is also an end view of four units driven in sequence and shows the fifth operation. The first driving unit has 40 been withdrawn and redriven in engagement with the fourth unit, leaving the first unit of permanent sheet piling permanently set in the ground and backfilled if necessary. The succeeding operations are merely repetitions of those already described and consist of withdrawing the units from the rear of the line and redriving them in front as the cores are removed and successive units of the permanent structure are assembled in the spaces between the side pieces.

In Fig. 11 the side pieces 2 2, of several units driven 50 in engagement are united by pins 5 5 etc. which are connected by links 16 16 etc. to horizontal stiffening beams 17 17. The opposite side pieces may be separated by some of the core sections, 9 9 left in position, by wedges 11 11, driven between their upper ends, by 55 jack screws 15 15, by struts, or by other suitable separators between the horizontal beams, thus leaving some or all of the driving units with unobstructed interior cavities. In Figs. 13 and 14 the upper ends of the side pieces 2 2, directly engage the flanges of the stiffening beams 17—17 and are separated by wedges 11, 11, driven between the latter.

I do not wish to limit the details of my driving units to the exact forms shown in the figures, but intend to cover the use of any suitable combination of detachable pieces forming a solid or hollow driving unit with

removable members which can be withdrawn to provide an interior space for setting or assembling a more permanent structure and protecting it from the earth until completed, as well as obviating the necessity of driving the permanent structure and avoiding the danger and injury to the latter that is often caused by impact, interference with obstructions and severe mechanical treatments incident to other methods of constructing sheet piling and other kinds of subterranean structures. Various modifications may be made in the character and details of the cores and side pieces, in the form and arrangement of the shoe or point, and method of securing it, in the connection of the tops of successive units, and in the means of stiffening them laterally and of maintaining the spacing between those on opposite sides of the trench after withdrawal of the cores. The figures shown illustrate simple and efficient types by which the operations can be effected.

I claim:

1. A driving unit with a substantially rectangular cross section made of a core and a plurality of separate detachable parts on two opposite sides and adapted to form and maintain a cavity in the ground. 85

2. A driving unit with a substantially rectangular cross section made with a core and a plurality of detachable parts on two opposite sides adapted to form and maintain temporarily a cavity in the ground, and afterwards to be withdrawn and used again. 90

3. A sectional driving unit made with a core and a plurality of detachable parts adapted to be driven in engagement with another unit and to provide with the latter a continuous open interior space with the exterior materials excluded by the outside sections of the units. 95

4. A driving unit essentially consisting of a sectional box with a closed cross section and detachable sides and bottom, adapted to engage an adjacent driving unit. 100

5. A driving unit essentially consisting of a sectional trough with rectangular cross section and detachable sides and bottom, adapted to engage on the open side with an adjacent driving unit. 105

6. A driving unit of rectangular cross section with a core and a plurality of longitudinal sections on two opposite sides detachably connected and adapted to be driven together. 110

7. A driving unit of rectangular cross section with a plurality of longitudinal sections detachably connected and adapted to be withdrawn separately. 115

8. A driving unit made with a plurality of longitudinal sections part of which may be detached and independently withdrawn, leaving an interior cavity. 115

9. In a driving unit a plurality of side pieces with their vertical edges interlocking with the vertical edges of adjacent units. 120

10. The combination in piling, of driving units each having a plurality of side pieces with their edges overlapping those of adjacent units. 120

11. The combination in piling, of driving units each having a plurality of side pieces and projections thereon adapted to engage adjacent units. 125

12. The combination in piling, of driving units each having a detachable projecting core adapted to engage a recess in an adjacent driving unit. 125

13. The combination in piling, of driving units, cores therefor, and detachable side pieces of said units projecting beyond said cores and adapted to form jaws to receive the projecting detachable core of an adjacent driving unit. 130

14. The combination in driving units, of, detachable side pieces thereof, and detachable core sections arranged to project beyond the edges of said side pieces on one side and located within their edges on the opposite side and being adapted to form temporary tongue and groove joints between adjacent driven units. 135

15. The combination in a driving unit of side pieces, a core and a detachable shoe adapted to separate the lower 140

- ends of said side pieces and provided with means for engaging the lower ends thereof.
16. In a driving unit a detachable shoe closing the spaces between the lower ends of the side pieces.
- 5 17. In a driving unit detachable clamps adapted to temporarily secure the shoe to the side pieces.
18. In a driving unit temporary detachable separators between the upper ends of the side pieces.
19. In piling, detachable horizontal side pieces adapted
- 10 to give lateral strength to and connect a series of driving units.
20. In a driving unit the combination of a plurality of detachable side pieces and a solid temporary removable core.
- 15 21. In a driving unit, the combination of a plurality of detachable side pieces, a detachable core and a detachable shoe.
22. In a driving unit the combination of a plurality of side pieces, a detachable core and a shoe.
- 20 23. In a driving unit the combination of a plurality of detachable side pieces, a detachable core, a detachable shoe and detachable clamps.
24. The combination in piling of successive driving units and lateral connections temporarily securing them
- 25 together.
25. The combination in piling of successive driving units and exterior stiffening pieces.
26. The combination in piling, of driving units, a plurality of side pieces therefor, and separators between the upper ends thereof.
- 30 27. The combination of sectional driving units each comprising a plurality of detachable parts adapted to form a line of parallel opposite sides and exclude earth and other material from the continuous open spaces between said sides.
28. The combination in piling of a plurality of sectional driving units, each comprising detachable sides, and cores, said units arranged in sets, and said units being adapted to form walls with open interior spaces closed at the ends and continuous through several of said units.
- 35 29. The combination in piling units, of side pieces, and detachable separators, and shoes adapted to connect and strengthen said side pieces, and together with said side pieces to exclude outside materials from the interior of said units.
